United States Patent Office

Des. 199,934
Patented Dec. 29, 1964

199,934

PAIR OF SPECTACLES

Farnham Blair, Arlington, Va., assignor to The Mini Company, Washington, D.C.

Filed Jan. 29, 1964, Ser. No. 78,404

Term of patent 14 years

(Cl. D57—1)

FIG. I

FIG. II

FIG. III

FIG. 1 is a top plan view of a pair of spectacles with temples partially folded;

FIG. 2 is a front elevational view thereof; and

FIG. 3 is a side elevational view.

The side not shown has substantially the same appearance as the side shown.

I claim:

The ornamental design for a pair of spectacles, as shown and described.
